UNITED STATES PATENT OFFICE.

HILARY J. HENNESSY, OF ST. PAUL, MINNESOTA.

RATCHET WINDING MECHANISM.

1,212,152.

Specification of Letters Patent.

Patented Jan. 9, 1917.

Application filed February 25, 1916. Serial No. 80,488.

To all whom it may concern:

Be it known that I, HILARY J. HENNESSY, a citizen of the United States, residing at St. Paul, in the county of Ramsey and State of Minnesota, have invented certain new and useful Improvements in Ratchet Winding Mechanisms, of which the following is a specification, reference being given therein to the accompanying drawing.

10 My invention relates particularly to ratchet winding mechanisms of hopper door operating shafts for cars and coal chutes, and handbrake shafts of passenger and freight cars.

15 The object of my invention is to provide a lever operated mechanism, wherein the possibility of danger to the operator is entirely eliminated, when releasing, while under load.

20 Another object of this invention, is to provide a ratchet winding mechanism wherein the customary dog or pawl is eliminated, thereby making it very easy by positive action to release load.

25 With the preceding and other objects in view the invention consists of the novel construction, combination and arrangement of parts to be described, illustrated and claimed.

30 Reference will now be had to the accompanying drawings forming part of this specification, the letters in the reference designate the corresponding parts in the several views, in which—

35 Figure 1 is a front elevation of the assembled ratchet winding mechanism which shows the shaft in a horizontal position and the lever in the vertical position. As the position of the shaft will not interfere with

40 the operation of this device, I show it in this position so as to more clearly illustrate the several views. Fig. 2 is a side elevation and partial section of the several parts assembled in their respective positions.

45 In the accompanying drawings, I show a steel plate section "a" upon which I have mounted my invention; this plate representing a rigid framing member of the car or chute.

50 "b" is the winding shaft which has a threaded end to receive the nut "k" said shaft is common to most winding mechanisms with the exception of a square end as shown at "j". Said shaft is journaled in 55 the plate "a" by the combined journal bearing and ratchet "d" which is securely fas-

tened to said plate "a" by rivets "n", at the right hand end of said shaft "b" the chain or cable is wound (not shown) which is also common to all winding mechanisms, the end of said shaft "b" is also secured at this end by nuts or keys to retard any lateral motion in said shaft (not shown).

"c" is a winding shaft ratchet wheel with an extended hub mounted on square end of 65 said shaft so as to allow horizontal travel on said shaft but to retard rotation about said shaft. Teeth are placed radially on both sides of said ratchet wheel on one side to engage with teeth in the combined journal bearing and ratchet "d", the teeth on the other side of said ratchet "c" engage with radial teeth in lever ratchet, "h" whose hub rotates about the hub on ratchet "c".

"e" is a collar which is threaded on to the 75 end of hub on ratchet "c".

"f" is a spring bearing against spring cap "g" which holds operating ratchet "h" in mesh with shaft ratchet wheel "c" which in turn is held in mesh with combined journal bearing and ratchet "d".

"p" is a spring bearing against spring cap "g" and winding shaft ratchet wheel "c" to keep said ratchet "c" in mesh with combined journal bearing and ratchet "d", independent of spring "f" and lever ratchet "h".

"g" is a spring cap on end of shaft "b", holding spring "f" in position and fastened to said shaft by the nut "k".

"i" is the operating lever which is further crummed on operating ratchet by the bolt "m" which is held by nut "l", said operating lever bears against spring cap "g" at the point designated by the letter "o".

I will now explain the operation of my 95 invention: In winding, operating lever "i" is moved back and forth which transmits the motion to lever ratchet "h" which engages with shaft ratchet wheel "c" turning winding shaft "b". At the end of each 100 stroke shaft ratchet wheel "c" engages with combined journal bearing and ratchet "d" which holds the load until another purchase is procured. In releasing the load operating lever "i" is moved outward the forked end 105 bearing against spring cap "g" at the point marked "o" pulling teeth on lever ratchet "h" out of mesh of teeth on shaft ratchet wheel "c" when teeth on lever ratchet "h" have cleared the teeth on shaft 110 ratchet wheel "c" the hub of said lever ratchet strikes collar "e" which moves shaft

ratchet wheel "c" along square fit at "j" on shaft "b" until teeth on shaft ratchet clear teeth on combined journal bearing and ratchet "d" thus releasing load and allowing it to turn shaft.

5 While in the drawings, forming a part of this application there is illustrated the preferred embodiments of my invention, it is to be understood that the elements therein can be varied or changed as to shape, proportion and exact manner of assemblage, without departing from the spirit of the invention.

10 Having designated and described the several parts and the operation of each sufficiently clear to enable those skilled in the art to thoroughly understand the same, what I claim and desire to secure by Letters Patent is:

15 20 1. In a ratchet winding mechanism, the combination with a winding shaft of a combined journal bearing and ratchet, and a winding shaft ratchet wheel and a lever ratchet substantially as described.

25 30 2. In a ratchet winding mechanism, a winding shaft, a combined journal bearing and ratchet, a winding shaft ratchet wheel having an extended hub, and mounted upon said winding shaft, and a lever ratchet, loosely mounted on the said extended hub of said winding shaft ratchet wheel.

35 40 3. In a ratchet winding mechanism, the combination with a winding shaft, of a combined journal bearing and ratchet with integral teeth, and a winding shaft ratchet wheel with integral teeth on both sides thereof, and an extended hub secured to said winding shaft for longitudinal movement but to prevent rotation about said winding shaft, of a lever ratchet with integral teeth

and an extended hub loosely mounted upon the hub of said winding shaft ratchet wheel, so as to allow longitudinal travel and rotation around hub of said winding shaft ratchet wheel and held from moving off hub of said winding shaft ratchet wheel by a collar secured to last named hub substantially as described. 45

4. In a ratchet winding mechanism, the combination with a winding shaft of a combined journal bearing and ratchet and a winding shaft ratchet wheel and a lever ratchet of a spring to keep said winding shaft ratchet wheel in mesh with said combined journal bearing and ratchet, substantially as described. 50

5. In a ratchet winding mechanism, the combination with a winding shaft, of a combined journal bearing and ratchet and a winding shaft ratchet wheel and a lever ratchet and a spring to keep said winding shaft ratchet wheel in mesh with said combined journal bearing and ratchet, of a spring to keep said lever ratchet in mesh with said winding shaft ratchet wheel, substantially as described. 55

6. In a ratchet winding mechanism, the combination with a winding shaft, of a combined journal bearing and ratchet and a winding shaft ratchet wheel and a lever ratchet and springs to keep said ratchets in mesh, of an operating lever, pivoted on said lever ratchet, with forked end integral, substantially as described. 60

In testimony whereof, I affix my signature in the presence of two witnesses. 65

HILARY J. HENNESSY.
